UNITED STATES PATENT OFFICE

MILLARD S. BLACK, OF HUNTINGTON PARK, CALIFORNIA

WELL TOOL

Application filed March 12, 1928. Serial No. 260,823.

This invention has to do with a well tool and relates particularly to a tool operable to engage or grip casing located in a well. It is a general object of the invention to provide 5 an improved and simplified casing gripping tool.

It is a general object of this invention to provide a casing engaging or gripping tool operable to tightly engage or grip a casing in a well. The present invention is capable of embodiment in various forms, making it suitable for a variety of uses. For instance, the invention may be used as a holding tool or spear, it being useful in a jar down spear as well as in a jar up spear. For purpose of example, I will refer to the invention as embodied in a tool for holding a casing against rotation, it being understood that this specific reference is not to be construed as a limitation or restriction upon the broader principles of the invention.

An object of my present invention is to provide a casing gripping tool in which the casing engaging members are mounted so that they are particularly effective and are reliable in operation.

A further object of this invention is to provide a tool of the character mentioned in which the casing engaging members may be actuated or made tight in engagement with the casing through rotation of the tool and/or longitudinal movement of the tool.

A further object of this invention is to provide a tool of the character mentioned in which the casing engaging members and the control or operating means therefor are combined and related in a simple effective manner.

The various objects and features of the invention will be best and more fully understood from the following detailed description of a typical form and application of the invention, throughout which description I refer to the accompanying drawings, in which:

Fig. 1 is a longitudinal detailed sectional view of a well casing showing the tool provided by this invention carried by a string of drill pipe and in operating engagement with a section of the casing. Fig. 2 is an enlarged

detailed sectional view of the tool showing it in the unactuated position, certain of the parts being shown in elevation. Fig. 3 is a view similar to Fig. 2 showing the tool actuated or set in the casing, and Fig. 4 is an enlarged sectional view of the body of the tool, being a view taken immediately below the middle portion of the body looking up at the body, with all other parts of the tool removed.

In setting forth my invention I will, for purpose of example only, describe it as applied to a tool for operation in a well casing to hold the casing against rotation or to grip the casing for rotation. I have shown the tool arranged in a string of well casing 10 including a plurality of sections A joined by couplings B. In the drawings the tool is shown carried by a string of drill pipe 11 and set in the casing 10 at a point immediately below a coupling B.

The tool comprises, generally, a main part or body 12, casing gripping or engaging means 13 carried by the body, and operating or control means 14 for the casing engaging means 13.

The body 12 is an elongate member forming a carrier for the other parts of the tool, and is preferably formed with an upper end portion 15 adapted to be connected with a string of drill pipe 11, or the like, a middle portion 16 carrying the means 13, and a lower end portion 17 carrying the control means 14.

In the particular form of body shown in the drawings the upper end portion 15 is provided in its upper end with a tapered screw-threaded socket 18 to receive the pin of a sub or tool joint section embodied in a string of drill pipe, or the like. The middle portion 16 of the body may be integral with the end parts and is shaped and proportioned to actuate the means 13, as will be hereinafter described: The lower end portion 17 of the body is in the form of a rod or stem projecting downwardly from the middle portion 16 to carry the means 14. The lower end of the part 17 is provided with a stop, for instance a nut 19, which serves to retain the means 14 in place.

The casing engaging or gripping means 13

is preferably a slip means embodying a plurality of wedge members or slips arranged symmetrically around the middle portion of the body so that they are operable from a collapsed or retracted position to an expanded or operating position where they engage the interior of the casing.

In accordance with my present invention, the slips 20 are mounted on the middle portion 16 of the body so that they move upwardly and radially outward and at the same time laterally or in a direction transverse of the longitudinal axis of the tool. In the particular construction illustrated, the middle portion of the body 16 is provided with a plurality of upwardly and radially outwardly extending faces 21 on which the slips 20 are carried. The faces 21 are pitched or angularly disposed so that they give the slips the desired radial movement as they move upwardly.

The slips are guided on the faces 21 so that they have the desired lateral movement as they move upwardly and radially. In the construction illustrated dovetailed guideways 22 are formed in the faces 21 and are pitched or angularly disposed with reference to the longitudinal axis of the tool to give the slips the desired lateral movement. The slips have ribs 23 formed on their inner or rear faces to slidably operate in the guideways 22. The outer faces of the slips 20 are made to extend parallel with the longitudinal axis of the tool and are made to conform generally with the curvature of the interior of the casing 10.

Where the tool is to be used in holding casing against rotation or for rotating casing the outer faces of the slips are preferably provided with casing engaging or gripping teeth 25 which extend vertically or in the direction of the longitudinal axis of the tool. If this tool is to be used as a spear the teeth may be arranged horizontally. In shaping or curving the outer faces of the slips I have found it practical to arrange the slips in the unactuated position shown in Fig. 2, mount the tool in a lathe and then turn the slips to the diameter desired for the retracted position. I then operate the slips to the extended position as shown in Fig. 3 and turn the slips to the diameter desired for the expanded position. In this way I have found it practical to obtain a proper fitting of the slips in the casing in spite of the lateral movement given the slips by the pitching of the guideways 22. It is to be understood, of course, that the gripping teeth 25 may be formed on the faces of the slips after the faces have been properly shaped.

In the preferred form of the invention a stop collar 26 is applied to the upper end portion 15 of the body adjoining the upper end of the middle portion 16 to form a positive stop for preventing the slips passing out of the upper ends of the guideways.

The control means 14 is in the nature of a tail piece slidably carried on the lower end portion 17 of the body. The tail piece includes an upper collar 30 slidable on the body portion 17, a lower collar 31 slidable on the body portion 17 and a plurality of leaf springs 32 extending between the collars and shaped to bear outwardly against the interior of the casing 10.

An over-hanging or inwardly extending flange 33 is provided on the upper end of the top collar 30 to hold lugs 34 which project outwardly from the lower ends of the slips 20. The flange 33 and lugs 34 cooperate so that the slips are moved longitudinally with the collar 30 and are free to expand radially in the desired manner.

The top collar 30 is adapted to be releasably held in a down or unactuated position by means of a pin 36 projecting from the body portion 17 and cooperating with a bayonet slot 37 in the collar. When the collar 30 is held down as shown in Fig. 2, the pin 36 is in the inner end of the bayonet slot 37 and the slips are down or unactuated. To release the collar 30, so that the collar is movable to actuate the slips along the faces 21, the body is rotated to disengage the pin 36 from the inner end of the bayonet slot, allowing the pin to move through the longitudinal portion of the slot. When the collar 30 has been released and the body moved downwardly the slips are operated to the position shown in Fig. 3.

From the foregoing description it is believed that the operation of the tool will be fully understood. The tool is applied to the lower end of a string of drill pipe 11, or the like, and lowered to the desired point in well casing 10. The parts of the tool are arranged as shown in Fig. 2 as it is lowered into the well. The springs 32 of the tail piece normally frictionally engage the interior of the casing 10. When the tool has reached the desired point the springs 32 hold the tail piece stationary so that the body can be rotated from the drill pipe to disengage the pin 36 from the inner end of the bayonet slot. The slips may then be operated into expanded or casing engaging position by downward movement of the body and, if necessary, by downward movement of the body coupled with rotation of the body.

In a tool to be used while casing is being unscrewed, the guideways 22 are preferably pitched or angularly disposed so that the tendency for the casing to rotate during the unscrewing operation merely tends to tighten the grip of the slips in the casing. The same action is obtained when the tool is used as a spear. To release the tool the drill pipe 11 is moved upwardly to lift the body from the slips, the slips release their grip on the casing allowing the parts to return to a position such as shown in Fig. 2 in which position the tool may be withdrawn from the well.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A well tool of the character described including, a body having flat faces extending longitudinally of the body and radially outward from the longitudinal axis of the body, slips operable longitudinally on said faces, and means whereby the slips are moved tangentially upon operation along the faces.

2. A well tool of the character described including, a body having faces extending longitudinally of the body and radially outward from the longitudinal axis of the body, slips operable longitudinally on said faces, and guide means whereby the slips are moved tangentially upon operation longitudinally along the faces.

3. A well tool of the character described including a body having faces extending longitudinally of the body and radially outward from the longitudinal axis of the body, slips operable on said faces, and means whereby the slips are moved obliquely upon operation along the faces, said means including angularly disposed slip guides at the faces.

4. A well tool of the character described including, a body having flat inclined faces, slips arranged to operate on the faces, means for operating the slips including a collar slidably connected with the body and directly connected with the slips and friction springs attached to the collar, and guide means for guiding the slips obliquely on said faces.

5. A well tool of the character described including, a body having flat inclined faces, slips arranged to operate on the faces, means for operating the slips including a collar slidably carried on the body and directly connected with the slips, a second collar, friction springs carried between the collars, and guide means for guiding the slips tangentially on said faces.

6. A well tool of the character described including, a body having flat inclined faces, slips arranged to operate on the faces, means for operating the slips including a collar slidably connected with the body and directly connected with the slips, and friction springs attached to the collar, the connection between the collar and slips including a flange on the collar and lugs on the slips co-operating with the flange, and guide means for guiding the slips tangentially on the faces.

7. A well tool of the character described including, a body having flat inclined faces, slips arranged to operate on the faces, means

for operating the slips including a collar slidably connected with the body and directly connected with the slips, a releasable connection between the body and collar, friction springs attached to the collar, and means whereby the slips are moved tangentially upon longitudinal movement on the faces.

8. A well tool of the character described including, slips, a body having flat slip carrying parts extending longitudinally of the body radially outwardly and tangentially, the slips being shiftable longitudinally on said parts.

9. A well tool of the character described including, slips, a body having straight slip carrying guides extending longitudinally of the body radially outwardly and tangentially.

10. A well tool of the character described including, a body having faces extending longitudinally of the body and radially outwardly from the longitudinal axis of the body, slips operable longitudinally on said faces, and means whereby the slips are moved tangentially upon operation along the faces, said means including ribs on the slips slideable in guideways in the said faces.

11. A well tool of the character described including, a body having faces extending longitudinally of the body and radially outwardly from the longitudinal axis of the body, slips operable longitudinally on said faces, and means whereby the slips are moved tangentially upon operation along the faces, said means including dovetailed ribs on the slips operable in guideways in the said faces.

In witness that I claim the foregoing I have hereunto subscribed my name this 3rd day of March, 1928.
